GOVERNING APPARATUS

Manious Gottlieb, Philadelphia, Pa., assignor to
Westinghouse Electric & Manufacturing Com-
pany, East Pittsburgh, Pa., a corporation of
Pennsylvania

Application June 28, 1939, Serial No. 281,595.

15 Claims. (Cl. 264—7)

My invention relates to a governing mechanism for a prime mover, for example, a steam turbine, and it has for an object to provide apparatus of this character capable of adjustment to secure operation of the turbine or prime mover over a wide speed range.

In certain industrial applications of steam turbines, it is necessary, not only that speed adjustment be provided for, but that the speed for which adjustment has been made shall be maintained irrespective of changes in load. If the application is to drive a paper mill, the thickness of the web of paper depends upon a number of factors including speed of the driving turbine. Accordingly, if the speed is adjusted for a certain paper web thickness, it is necessary to maintain the speed substantially constant irrespective of load variations occasioned by variations in the requirement for process steam used for heating the mill rolls. In addition to constancy of speed for given conditions with load variations, the conditions may vary so that operation of the turbine over a wide speed range is necessary. Therefore, a further and more particular object of my invention is to provide a governing mechanism adjustable to give a wide speed range and wherein each speed is maintained substantially constant irrespective of load variations.

A further object of my invention is to provide a pressure transformer between the governor and the admission valve of a prime mover and wherein the movable or controlling part of the transformer may have relatively large clearance to minimize friction and wherein difficulties on account of mechanical interference and hydraulic reaction are avoided.

A further object of my invention is to provide a governing mechanism including a pressure transformer capable of giving speed compensation for variations in load.

A further object of my invention is to provide a pressure transformer between a centrifugal governor and the admission valve of a prime mover and wherein the transformer is capable, not only of giving speed compensations for variations in load, but also speed compensations for variations in scale effect of the centrifugal governor spring means so that, at each speed, over the relatively wide range, the percentage of regulation or speed variation from no load to full load may be maintained at a minimum.

These and other objects are effected by my invention as will be apparent from the follow-

ing description and claims taken in connection with the accompanying drawings forming a part of this application, in which:

Fig. 1 is a sectional view showing a turbine with the improved governing mechanism applied thereto;

Fig. 2 is an enlarged sectional view showing the centrifugal governor and transformer of Fig. 1;

Fig. 3 is a view similar to Fig. 2 but showing a second embodiment;

Fig. 4 is a view similar to Fig. 2 but showing a fourth embodiment;

Fig. 5 is a view similar to Fig. 2 but showing a third embodiment having means to secure an increased degree of speed compensation;

Fig. 5a is a diagram illustrative of principles of operation of the embodiment shown in Fig. 5;

Fig. 6 illustrates a modified form of the arrangement shown in Fig. 3; and,

Fig. 7 shows a modified form of servo-motor used with the governing apparatus of Figs. 1 and 2.

In Fig. 1, there is shown a steam turbine, at 10, having an admission valve 11 controlled by a servo-motor, at 12, which operates in response to transformed oil pressure furnished by the transformer, at 14, controlled by the centrifugal governor, at 15.

The turbine, at 10, has, at one end thereof, the vertical casing 16 with the vertical governor spindle 17 rotatably mounted therein and driven from the turbine rotor 18 by means of beveled gears 19 and 20. The lower end of the spindle 17 drives a pump, at 21, and its upper end drives the centrifugal governor, at 15. Also, the casing 16 includes an upper casing element or cover 22 enclosing the centrifugal governor, at 15, and the transformer, at 14; and, due to the internally projecting flange 23, it also contributes to the structure and operation of the transformer.

The centrifugal governor, at 15, includes a drum construction 24 provided with a transversely extending leaf spring 25 having its ends attached to the drum. Flyweights 26 are attached to the leaf spring and centrifugal force acting thereon tends to produce movement thereof with deflection of the leaf spring. The leaf spring has a bent or inverted U-shaped portion 27 serving to transmit thrust from the centrifugal governor to the transformer in the manner hereinafter described.

The pressure transformer, at 14, includes a body 28 which depends from the flange 23 and has a cylinder 30 comprising bore portions 32,

33, and 34 of smaller diameter than the intermediate bore portions 35 and 36. The upper end of the cylinder is closed by a plug 31. A tubular plug 37 has a close sliding fit within the upper bore portion, the intermediate bore portion 33 provides a guide for the piston or plunger portion 38 of the transformer relay 39, and the lowermost bore portion 34 receives a bushing 40 for the depending relay stem 41. The intermediate or enlarged bore portion 35 provides an exhaust space or chamber and the portion 36 a pressure chamber or space.

The plug 37 has an internal axial bore 43 providing an opening through its lower surface 44, the latter being normal or radial to the plug axis and serving the purpose to be hereinafter described.

The flange 23 has passages 45 and 46 registering, respectively, with ports or passages 47 and 48 formed in the body 29 and communicating with the cylinder 30 between the plugs 31 and 37. Oil, or other appropriate liquid, is supplied under suitable pressure by the conduit 50 through the registering passages 45 and 47 to the cylinder 30, the port or passage 47 being provided with the metering orifice 51. The registering passages 48 and 46 are connected to the conduit 52, leading to the pressure responsive servo-motor, at 12.

The relay 39 has a cup 54 formed at its upper end, the cup being in covering relation with respect to the lower or discharge end of the plug bore 43 and having a sharp annular edge 55 defining, with the radial face or seat 44, a radially-disposed annular escape orifice, whose flow area is restricted by upward movement of the relay element 39 and vice versa.

Thus, there is an enclosed space, provided by the bore 43, the upper portion of the cylinder 30, the passages 48, 46 and 52, and the pressure chamber 56 of the servo-motor, to which liquid is supplied by means of the metering orifice 51 and from which liquid escapes by means of the annular escape orifice. Therefore, the pressure existing in such space depends upon the flow area of the annular escape orifice, the pressure increasing with decrease in flow area and vice versa; and, as the flow area of the annular escape orifice is determined by the relay 39, it will be apparent that movement of the relay secures a transformed oil pressure in the space.

The relay 39 is moved the very slight amount required to vary the transformed oil pressure by the opposing forces due to centrifugal force of the flyweights and to transformed oil pressure acting on the piston area provided by the cup valve 54, the centrifugal force of the flyweights being opposed by the deflection resistance of the leaf spring 26.

The relay 39 is preferably provided with a downwardly-facing annular piston area 58 exposed to the pressure existing in the enlargement or chamber 36. The piston area of the cup valve 54 is preferably made somewhat larger than the annular piston area 58 so that, with transformed oil pressure supplied to the chamber 36, a sufficient downwardly-acting differential pressure force will be effective to keep the relay stem 41 in contact relation with respect to the U-shaped spring portion 27.

Preferably, oil under transformed pressure is supplied from the passage 46 through an adjustable orifice 59 to the air bell or chamber 60 in the upper portion of the cover 22, and, from the latter, oil passes through the bore 61 formed in

the body 29 to the lower bore or chamber 36 for action on the annular piston area 58.

With the form of the invention shown in Figs. 1 and 2, assuming a decrease in load, the speed would increase, causing the bent portion 27 of the leaf spring to move the relay 39 upwardly to decrease the flow area of the annular orifice, thereby increasing the transformed oil pressure, and this operation continues until the downwardly-acting force of the transformed oil pressure acting on the piston area provided by the cup valve balances the increase in centrifugal force. The increase in transformed oil pressure is not applied immediately to the lower chamber or bore 36 for action on the piston area 58 but in a delayed manner due to the restricted rate of flow permitted by the adjustable orifice 59. As the pressure gradually increases in the lower bore or chamber 36 it acts on the piston area 58 to cause further decrease in the annular orifice and increase in the transformed oil pressure, such further increase in transformed oil pressure bringing about further restriction of opening of the admission valve to minimize speed change due to load change so that the speed may be restored substantially to the same value it had before the load change. On the other hand, an increase in prime mover load is followed by contrary operation, the delayed effect of change in transformed oil pressure assuring of opening of the admission valve sufficiently to effect substantial speed correction with increase in load.

While the extent of speed correction or compensation depends on keeping the differential piston effect at a minimum for maintaining the relay stem 41 in contact relation with respect to the leaf spring, the extent of compensation as well as securing a desired differential effect for the purpose indicated is assured by having the pressure chamber 36 communicate with the drain passage 63 by means of a needle valve 64. If the needle valve 64 is wide open, then there can be no accumulation of pressure in the chamber 36 with the result that the piston area 58 would be ineffective and the downwardly-acting transformed oil pressure would be opposed entirely by the centrifugal force effect of the flyweights. On the other hand, as the valve 64 restricts more and more escape from the chamber 36, the higher will be the maximum pressure in the latter, until, with the needle valve 64 entirely closed, it is possible to provide for transformed oil pressure in the chamber 36.

As the relay 39 does not have to control pressure and exhaust ports, it merely having a cup valve 54 in covering relation with respect to the discharge opening 43 to define the annular escape orifice and the chamber provided by the bore 35 to which said orifice discharges being connected to the drain passage 63, it will be apparent that the relay may have large clearances with respect to cooperating parts with the result that it may move freely and in a substantially frictionless manner. Furthermore, any chance of binding or of mechanical interference of closely fitting parts is avoided and there are no sharp edges, and port corners to wear and impair accuracy of operation. Also, as the annular escape orifice provided between the thin edge 55 of the cup valve and the seat 44 is directed radially, there is no axial component of hydraulic reaction present and tending to introduce a variation or error in the operation of the governor.

Speed adjustment of the form of the governing apparatus shown in Figs. 1, 2, and 7 is secured

by varying the position of the plug 37 in the bore 32, the plug being raised and lowered, for example, by means of the crank portion 65 engaging the slot 66 formed in the plug 37, the crank portion being carried by a stub shaft 81 turned by means of worm gearing, at 88, operated by a speed changer shaft 89. If the plug 37 is raised, it will be apparent that the operating speed will be increased and vice versa, that is, by means of this adjustment, the governor is rendered capable of operating over a wide range of operating speeds and functioning at each operating speed to provide for governing of the turbine from no load to full load.

The oil under transformed pressure is supplied by the conduit 52 to the enclosed pressure chamber 56 of the servo-motor, at 12, the pressure chamber being preferably defined by a movable abutment 68a, inner and outer bellows elements 67a and 68a, and the body structure 69a of the servo-motor. The servo-motor body structure includes the usual pilot valve and operating cylinders 11 and 12, a pilot valve 13 being arranged in the pilot valve cylinder and an operating piston 14 being located in the operating cylinder 12. The pilot valve 13 has suitable lands, as illustrated, for controlling admission and exhaust ports for securing the admission and exhaust of motive fluid to opposite ends of the operating cylinder 12 to effect movement of the operating piston 14. A spring 15 exerts its force on the upper end of the pilot valve to keep the lower end thereof in contact relation with respect to the movable abutment 68a.

The operating piston 14 has a stem 11 connected to the admission valve 11 and the stem is pivoted at the intermediate point 18 of a lever 19, one end of the latter being pivoted, at 89, to the body structure 69a, and the other end being connected to the rod 81 attached to the lower end of the spiral spring 82, the upper end of the latter being attached, by means of the rod 83 to the movable abutment 68a.

This follow-up mechanism provides for changing the force of the spring 82 to compensate for change in transformed oil pressure in the chamber 56 so as to restore the pilot valve to neutral position. In other words, assuming a change in load, the transformed oil pressure changes with the result that the pilot valve 13 is moved to control the admission and exhaust of motive fluid to the operating cylinder 12 so as to move the admission valve 11 in an opening or closing direction, depending upon the direction of load change; and movement of the operating piston 14 and of the valve 11 will continue until the change in force of the spring 82 effected by such movement compensates for the change in force of fluid pressure acting on the abutment 68a, whereby the latter is restored to a position such that the pilot valve 13 is brought to neutral or cut-off position, whereupon movement of the operating piston and of the admission valve ceases and the steam admission flow area of the latter remains fixed until the load again changes.

In Fig. 3, there is shown a second embodiment of the invention and which is similar, in general, to that already described except that, in addition to the leaf spring 28, the governor includes a load spring 85 and a modified form of speed changer, these differences necessitating a different arrangement of fluid passages. The body 29a depends from a flange 86 attached to the flange 23a and the hollow plug 37a is fixed in the upper end of the bore 32a adjacent to the

closure plug 31a. The hollow plug 37a has upper metering orifices 51a connected to the pressure supply passages 47a, 45a, and 50, and lower ports 51 connected to the passages 48a, 46a, and 52.

The depending body 29a has an external threaded connection 88 with respect to the speed changer nut 88a having external worm teeth 89 meshing with the worm 90 on the speed changer shaft 91. The lower end of the speed changer nut 88 engages a roller thrust bearing 92, which, in turn, engages the follower 93 for the upper end of the load spring 85. The lower end of the load spring engages a follower or abutment 94 which has a thrust connection with respect to the bent portion 21 of the leaf spring 28. Thus, not only is the centrifugal effect of the flyweights opposed by the leaf spring 27 and by the load spring 85, but the force of the latter may be varied to vary the speed setting by operation of the speed changer shaft 91, an increase in speed setting being secured by increase in force of the load spring 85 and vice versa.

In the forms of the invention so far described, the arrangement is such that, with an increase in speed, the relay 39 is moved upwardly slightly to increase the transformed oil pressure, that is, a decrease in load calls for an increased transformed oil pressure and vice versa. The invention may be arranged to secure the opposite relation, that is, with a decrease in load, instead of the transformed oil pressure increasing, it decreases. Accordingly, in Fig. 4, there is shown an embodiment which is similar to Fig. 3 except that the transformer is reversed. In this modification, the depending body 29b is provided with a plug 37b at the lower, instead of the upper, end thereof, and the plug has a central bore 43b whose upper escape end is bounded by a radial seat 44b with which cooperates the inverted cup 54b of the relay 39b. As before, oil from a suitable source is supplied through a metering orifice 51b to the bore 43b and the latter is connected by means of passages 45b and 46b to the pipe or conduit leading to the servo-motor. The intermediate or drain chamber 35b receiving oil escaping from the radially directed annular orifice is connected to the drain passage 63b.

The cover 22b is provided with an air bell or chamber 66b connected, by means of the adjustable orifice 59b, to the transformed oil pressure space including the passages 46b and 48b and the bore 43b, and the air bell is connected by means of a passage 61b to the pressure chamber 36b to which is exposed the upwardly-facing piston area 58b of the relay 39b. The chamber 36b preferably has valved communication 64b with respect to the drain passage 63b. A spring 66 preferably exerts its force on the upper end of the relay, which force, together with that of the fluid pressure acting on the upwardly-facing piston area 58b, acts in opposition to the fluid pressure force acting on the piston area of the cup valve 54b to keep the stem 41b in contact relation with respect to the bent portion 27 of the leaf spring.

With the form of invention shown in Fig. 4, the principle of operation is substantially the same as that described in connection with Fig. 3 except that, instead of the transformed oil pressure increasing with a decrease in load and vice versa, such pressure decreases and vice versa.

While the governing arrangements so far described are capable of governing over a relatively wide speed range with a reasonably small speed

change from no load to full load at each operating speed, nevertheless, there is a droop or increased percentage of speed change, from no load to full load as the operating speed is lowered. For example, referring to diagrammatic Fig. 5a, and comparing the speed change from no load to full load to secure the desired transformed oil pressure change, for example, 40 pounds at no load to 15 pounds at full load, if, at a speed setting of 6000 R. P. M., the percentage of regulation is .02 percent from no load to full load, then, at the setting of 1000 R. P. M., the speed change from no load to full load may be of the order of 7½ percent. Thus, there is a relatively greater speed droop at the lower end of the speed range than at the higher end thereof. This is due to:

(a) The differential area of the transformer relay is limited to effect a small downward force so that the relay will, at all times, maintain contact with the flyball element. Now, since the transformed oil pressure, which varies with the turbine load, acts on this differential area, it will be obvious that the net downward force also varies with the transformed oil pressure. Therefore, there is a slight change in speed caused by the change in transformed oil pressure.

(b) In any type of relay, some travel, however small, is necessary to produce a change in flow across its control edge or escape orifice; and, since the system is not scaleless, a slight change in speed is needed to produce this relative travel.

Since the force necessary to obtain a given change in transformed oil pressure is the same regardless of the operating speed and since the available power of the speed responsive element varies with the scale of the spring, it is evident that, at the lower speeds, a relatively larger percentage of speed change is needed to cause a change in transformed oil pressure than is required for such a change at higher speeds, this being obvious from Fig. 5a, wherein it will be seen that, if the speed setting is decreased, the percentage of speed change from no load to full load increases.

In Figs. 5 and 6, there are shown means for compensating for the aforementioned causes of speed droop. Absolute speed compensation is accomplished, without any added friction, by providing a definite downward force on the transformer relay 39c by means of a small piston, in Fig. 5, and by means of a spring, in Fig. 6. Now, since there is a definite downward force on the transformer relay which will prevent the relay leaving contact with the flyball element, the differential area of the relay can now be made so that an increase in transformed oil pressure causes an upward force on the relay corresponding to the force needed to move the relay to its new position, thus establishing equilibrium at a different transformed oil pressure without the need of speed change at any operating speed. In other words, the upwardly-acting differential pressure force may be sufficient to compensate for the scale effect of the spring so that, for a wide range of operating speeds and at each operating speed from no load to full load, the relay assumes an equilibrium position such that steam is so admitted to the turbine as to secure operation at substantially a constant speed.

In Fig. 5, the governing and transformer arrangements are similar to Fig. 3 except that, instead of the piston area of the cup valve 54 being larger than the piston area 58, as in Fig. 3, the

reverse is true in Fig. 5, the piston area 58c being sufficiently larger than the piston area of the cup valve 54c to secure an upward differential piston force to compensate for the change in scale effect of the governing spring means. This relationship of piston areas necessitates the employment of other means to keep the relay stem 41c in contact relation with respect to the flyball mechanism. Accordingly, the relay carries a piston 100 arranged to be acted upon by fluid pressure so as to exert a downward force on the relay sufficient to maintain the contact relation.

The introduction of the piston 100 calls for changes in detail of the fluid pressure passages of Fig. 5, as compared to Fig. 3. Instead of the pressure supply passage 47a communicating through orifices 51a with the plug bore 43a, as in Fig. 3, the pressure supply passage 47c has a vertical end portion aligned and communicating with the plug bore 43c, the plug 37c having lower openings 37c communicating with the transformed oil pressure passage 46c. The metering orifice for supplying oil to the transformed oil pressure space is comprised by the annular area 51c between the periphery of the piston 100 and the interior of the bore 43c, and the pressure difference across this orifice provides the downwardly-acting force to keep the relay in contact relation with respect to the flyweight mechanism.

In Fig. 6, the arrangement is similar to Fig. 3 so far as the metering orifice 51d is concerned and the relationship of piston areas 58d and 54d is the same as that described in connection with Fig. 5. As the piston area 58d is made sufficiently larger than the piston area of the cup valve 54d to compensate for change in scale of the governor spring means, as in Fig. 5, it is necessary to employ means for maintaining contact relation of the relay 39d with the flyweight mechanism. Accordingly, a spring 101 is arranged within the plug bore 43d and has its lower end bearing on the relay 39d to maintain the contact relation.

Fig. 7 shows a transformer and servo-motor arrangement which is similar in principle to that of Fig. 1 except that, by having the servo-motor pilot valve aligned with the transformer some simplification of structure and arrangement of fluid passages is provided. The bore 43e of the plug 37e has its upper end in communication with the pilot valve cylinder 102 constituting an upward extension of the body 29e. A servo-motor pilot valve 103 fits the cylinder and it controls communication of the pressure and exhaust ports 104 and 105 with passages 107 leading to opposite ends of the operating cylinder 108 having an operating piston 109 therein. The pilot valve 103 is made hollow for a substantial portion of its length, is open at the bottom, and it carries an axially-arranged stem 110. The lower end of the stem engages an abutment 111 for the upper end of the spiral spring 112, the lower end of the latter being supported by the body structure 29e.

Follow-up mechanism associated with the operating piston rod 113 and including spring means cooperates with the upper end of the stem 110. As shown, such follow-up mechanism includes a lever 114 having one end pivotally connected at 115 to the rod 113, being fulcrumed at an intermediate point 116, and having its other end pivotally connected at 117 with respect to a rod 118 engaging an abutment 119 for the upper end of the spring 120, the lower end of the latter engaging an abutment 121 which contacts with the upper end of the rod 118.

Liquid is admitted to the hollow interior of the pilot valve 103 and to the lower portion of the cylinder 102 by means of one or more metering orifice ports 51e provided in the pilot valve and in communication with the high pressure port 104. The space included within the hollow pilot valve, within the lower portion of the cylinder 102 and in the bore 43e, therefore, constitutes the transformed oil pressure space to which oil is admitted by the metering orifice 51e and from which oil escapes by means of the radially-directed annular orifice defined between the cup valve 54e and the lower end 44e of the plug 37e.

The lower end of the cylinder 102 is connected by a passage 124 with the space 36e to which is directly exposed the downwardly-facing piston area 58e of the relay 39e, the passage 124 including an adjustable orifice 125. An air bell 126 communicates with the chamber 36e, the passages affording this communication being associated with the drain passage 63e for the drain space or chamber 35e and a valve 64e controls communication of the drain passage to any desired extent with the chamber 36e. It will, therefore, be apparent that the passage 124, the adjustable orifice 125, and the air bell constitute an accumulator or impedance means, which, as before, provides for delayed application of transformed pressure in the chamber 36e. If the valve 64e is closed, then the maximum pressure accumulating in the chamber 36e is the transformed oil pressure, but the maximum may be less to any desired extent depending upon the adjustment of the valve 64e.

From the structure described, it will be apparent that the governing and transformer apparatus of Figure 7 is identical in principle to that shown in Figures 1 and 2. Instead of having the metering orifices associated with the hollow plug 37 and providing a separate pressure chamber 55 for the servo-motor pilot valve, as shown in Figure 1, in this view, the pilot valve aligned with the transformer is constructed and arranged to provide both the metering orifices and to function as its own pressure responsive device.

Transformed oil pressure provided in the lower portion of the cylinder 102 provides an upward force acting on the pilot valve. In addition to this force, the pilot valve is also acted upon by the force of the springs 112 and 128. Assuming that the pilot valve 103 is in neutral cut-off position and that a change in transformed oil pressure occurs due to a change in load, then the effect thereof is to upset the equilibrium condition of forces for neutral pilot valve position with the result that the latter is moved, thereby bringing about connection of the passages 107 with the pressure and exhaust ports 104 and 105 so that motive fluid is admitted and exhausted to the operating cylinder 108 to move the operating piston. The operating piston 109 moves in consequence to adjust the steam admission valve and this movement is transmitted through the follow-up mechanism to change the force of the spring 128, the follow-up movement continuing until the force of the latter spring is changed sufficiently to compensate for the change in force of transformed oil pressure acting on the pilot valve, whereupon the latter will be restored to neutral position, when the operating piston and admission valve have moved suitably to the load change.

While I have shown my invention in several forms, it will be obvious to those skilled in the art that it is not so limited but is susceptible of various other changes and modifications with-

out departing from the spirit thereof, and I desire, therefore, that only such limitations shall be placed thereupon as are specifically set forth in the appended claims.

5. What I claim is:

1. In governing apparatus, a pressure-responsive device; means for developing force which varies as a function of speed; spring means; a thrust member acted on by the resultant of forces of said first means and of the spring means; speed-changing means; means including said pressure-responsive device for providing a space for fluid under pressure; said last-named means having an escape port; a member in thrust-transmitting relation with respect to the thrust member and having covering relation with respect to said escape port to define an escape orifice; means for supplying fluid to said space so that variation in the escape orifice provides for variation in fluid pressure in the space; first compensating means responsive to fluid pressure changes in said space due to temporary speed changes incident to load changes to effect speed compensation with change in load; said first compensating means including a piston area formed on said member in opposed relation to the piston area provided by the portion thereof subject to space pressure at the escape orifice, means providing a chamber for the first piston area, and means providing for lagging relation of change in pressure in said chamber relative to that in said space; and second compensating means for effecting speed compensation incident to speed adjustment of the governor, whereby said governing system may govern the prime mover over a wide speed range with minimized speed variations at each speed setting from no load to full load; said second compensating means including a disc carried by said member and arranged in a cylindrical bore 20 providing said escape port, the disc dividing the bore into a portion forming a part of said pressure space and a portion providing a fluid-pressure supply space and cooperating with the wall of the bore to provide an orifice affording communication of the supply space with said pressure space, the pressure of fluid in the supply space acting on the disc to exert a force on said member to keep the latter in thrust-transmitting relation with respect to the thrust member so that said piston areas may have a differential action sufficient to provide for force exerted on the member to compensate for the spring scale incident to speed adjustment over the wide speed range.

55. 2. In governing apparatus, a pressure-responsive device; means for developing force which varies as a function of speed; spring means; a thrust member acted on by the resultant of forces of said first means and of the spring means; speed changing means; means including said pressure-responsive device for providing a space for fluid under pressure; said last-named means having an escape port bounded by a surface extending transversely of the latter, a member in thrust-transmitting relation with respect to the thrust member and having covering relation with respect to said port and cooperating with said surface to define a radially-directed circular escape orifice; means for supplying fluid to said space so that variation in the escape orifice provides for variation in the fluid pressure in the space; first compensating means responsive to fluid pressure changes in said space and due to temporary speed changes incident to load changes to effect speed compensation with change in load; said first

compensating means including a piston area formed on said member in opposed relation to the piston area provided by the portion thereof subject to space pressure at the escape orifice, means providing a chamber for the first piston area, and means including a passage connecting the pressure space and said chamber and providing for lagging relation of pressure changes in said chamber relative to said space; and second compensating means for effecting speed compensation incident to speed adjustment of the governor, whereby said governing system may govern the prime mover over a wide speed range with minimized speed variations at each speed setting from no load to full load; said second compensating means including a device for exerting force on said member in a direction to maintain the latter in thrust-transmitting relation with respect to the thrust member so that said first piston area may be made sufficiently larger than the piston area of the member bounded by the annular orifice to exert force on said member compensating for changes in transformed fluid pressure and changes in spring scale.

3. In governing apparatus, a pressure-responsive device; means for developing force which varies as a function of speed; spring means; a thrust member acted on by the resultant of forces of said first means and of the spring means; speed-changing means; means including said pressure-responsive device for providing a space for fluid under pressure; said last-named means having an escape port bounded by a surface extending transversely thereof; means including an orifice for supplying fluid under pressure to said space; a member in thrust-transmitting relation with respect to said thrust member and in covering relation with respect to said escape port and cooperating with said surface to define a radially-directed circular escape orifice; first compensating means responsive to fluid pressure changes in said space and due to temporary speed changes incident to load changes to effect speed compensation with change in load; said first compensating means including a piston area formed on said member in opposed relation to the piston area provided by the portion of the member subject to space pressure and bounded by the annular orifice, means providing a chamber for the first piston area, means including a passage connecting said pressure space and the chamber to provide for lagging relation of pressure changes in the chamber relative to the space; and second compensating means including a device for applying force to said member to maintain the latter in thrust-transmitting relation with the thrust member and to compensate for changes in scale of said spring means incident to speed adjustment of the governor effected by operation of the speed-changing means, whereby said governing system may govern the prime mover over a wide speed range with minimized speed variations at each speed setting from no load to full load.

4. In governing apparatus, a pressure-responsive device; means for developing force which varies as a function of speed; spring means; a thrust member acted on by the resultant of forces of said first means and of the spring means; speed-changing means; means including said pressure-responsive device for providing a space for fluid under pressure; means including an orifice for supplying fluid to said space; said last-named means having an escape port bounded by a

surface extending transversely thereof; a member in thrust-transmitting relation with respect to the thrust member and provided with a cup having an annular sharp edge cooperating with said flat surface to define a radially-directed circular orifice; first compensating means responsive to fluid pressure changes in said space and due to temporary speed changes incident to load changes to effect speed compensation with change in load; said first compensating means including a piston area formed on said member in opposed relation to the piston area provided by the cup and bounded by the annular orifice, means providing a chamber for the first piston area, means providing a passage affording communication between the pressure space and said chamber and including an air bell, and means providing an orifice in said passage between the air bell and the pressure space; and second compensating means for effecting speed compensation incident to speed setting adjustment of the governor, whereby said governing system may govern the prime mover over a wide speed range with minimized speed variations at each speed setting from no load to full load; said second compensating means including a device acting on the member to maintain the thrust-transmitting relation thereof with respect to the thrust member in order that said piston area may have such a differential relation as to exert force on the member to compensate for changes in scale effect of said spring means.

5. In governing apparatus, a pressure-responsive device; means for developing force which varies as a function of speed; spring means; a thrust member acted on by the resultant of forces of said first means and of the spring means; speed changing means; means including said pressure-responsive device for providing a space for fluid under pressure; said last-named means having an escape port for the pressure space; a member in thrust-transmitting relation with respect to the thrust member and in covering relation with respect to said port to define a circular escape orifice bounding a first piston area thereof; means for supplying fluid to said space so that variation in the escape orifice provides for variation in fluid pressure in the space; said member having a second piston area arranged in opposed relation to the first area; means providing for application of fluid pressure from said space to said second piston area; and biasing means for maintaining said member in thrust-transmitting relation with respect to the thrust member in order that the second piston area may be made sufficiently larger than the first to compensate for the scale of said spring means incident to speed adjustment.

6. In governing apparatus, a pressure-responsive device; means for developing force which varies as a function of speed; spring means; a thrust member acted on by the resultant of the forces of said first means and of the spring means; speed-changing means; a pressure transformer providing transformed fluid pressure for action on the pressure-responsive device; said transformer including a control member in contact relation with respect to said thrust member and serving to secure changes of transformed fluid pressure in predetermined relation with respect to governing force changes; means responsive to transformed fluid pressure changes due to temporary speed changes incident to load changes to effect speed compensation with change in

load; and means providing for the application of transformed pressure to the control member to secure modification of the transformed pressure to compensate for changes in scale of said spring means incident to adjustment of the speed-changing means over a wide speed range in order to minimize speed variations at each speed setting from no load to full load.

7. In governing apparatus, a pressure-responsive device; a centrifugal governor including flyweights, spring means, and a thrust member acted on by opposing effects of the flyweights and of the spring means; a pressure transformer providing transformed fluid pressure for acting on the pressure-responsive device; said transformer including means providing an enclosed transformed fluid-pressure space in communication with the pressure-responsive means and provided with an escape port bounded by a surface extending transversely of the latter and a member arranged in covering relation with respect to the port and cooperating with said surface to define a radially-directed circular escape orifice and in thrust-transmitting relation with respect to said thrust member; compensating means responsive to transformed fluid pressure changes due to temporary speed changes incident to load changes to effect speed compensation with change in load; said compensating means including a piston area formed on said member in opposed relation to the piston area thereof bounded by the annular orifice, means providing a chamber for the first area, and means including a passage between the transformed fluid-pressure space and said chamber and providing for lagging relation of pressure changes in said chamber relative to the transformed pressure space.

8. In governing apparatus, a pressure-responsive device; a centrifugal governor including flyweights, spring means, and a thrust member acted on by opposing effects of the flyweights and of the spring means; a pressure transformer providing transformed fluid pressure for acting on the pressure-responsive device; said transformer including means providing an enclosed transformed fluid-pressure space in communication with the pressure-responsive means and provided with an escape port bounded by a flat surface extending normally with respect thereto, means including an orifice for supplying fluid under pressure to said space, a member in thrust-transmitting relation with respect to said thrust member, and a cup carried by the member and having a thin annular edge cooperating with said flat surface to provide a radially-directed circular escape orifice; and compensating means responsive to transformed fluid pressure changes due to temporary speed changes incident to load changes to effect speed compensation with change in load.

9. In governing apparatus, a pressure-responsive device; a cylinder; means providing an enclosed space in communication with said pressure-responsive device and having an escape port opening into one end of the cylinder and axially aligned with the latter; said means having a surface bounding the exit end of the port and extending transversely with respect to the axis of the latter; means including an orifice for supplying pressure fluid to said space; speed responsive means operated by the prime mover and having a thrust member aligned with the axis of said cylinder; an elongated member having a stem at one end in abutting relation with respect to said thrust member, having a cup in covering

relation with respect to the exit end of said port and cooperating with said flat boundary surface to provide a radially-directed annular escape orifice, and having a piston portion fitting said cylinder, the portion of said cylinder between one end of the piston portion and said port providing a drain space for the annular orifice and the portion of the cylinder extending beyond the other end of the piston providing a pressure chamber; means providing a passage connecting said space and said pressure chamber and including an air bell; and means providing an orifice in said passage between said space and the air bell.

10. In governing apparatus, a pressure-responsive device; flyweights operated by the prime mover; spring means; a thrust member acted on by the resultant of forces due to the flyweights and to the spring means; means cooperating with the spring means and providing for adjustment of the speed setting; means including said pressure-responsive means and providing a space for liquid under pressure; said last-named means having a discharge port for said space; a member in thrust-transmitting relation with respect to said thrust member and cooperating with said port to define an escape orifice; means for supplying liquid to said space so that the pressure therein is a function of the flow area of the escape orifice; means for maintaining said member in thrust-transmitting relation with respect to the thrust member; and means including the abutment area of the portion of said member at the orifice subject to pressure of said space and an opposing piston area subject to said pressure to provide a differential effect compensating for the change in spring scale incident to change in speed setting.

11. In governing apparatus, a pressure-responsive device; means providing an enclosed space in communication with said pressure-responsive device and having an escape port whose discharge end is bounded by a flat surface; means including an orifice for supplying pressure fluid to said space; speed responsive means operated by the prime mover and having a thrust member; means providing a guide aligned longitudinally with said port and thrust member; and an elongated member having a stem at one end in abutting relation with respect to said thrust member, having a cup in covering relation with respect to the exit end of said port and cooperating with said flat boundary surface to provide a radially-directed annular escape orifice, and having a slide portion fitting said guide.

12. In governing apparatus, a pressure-responsive device; means providing an enclosed space in communication with said pressure-responsive device and having an escape port whose discharge end is bounded by a flat surface; means including an orifice for supplying pressure fluid to said space; speed responsive means operated by the prime mover and having a thrust member; means providing a guide aligned longitudinally with said port and thrust member; an elongated member having a stem at one end in abutting relation with respect to said thrust member, having a cup in covering relation with respect to the exit end of said port and cooperating with the flat boundary surface to provide a radially-directed annular escape orifice, and having a slide portion fitting the guide; the end of said slide portion remote from the port providing a piston area in opposed relation to that provided by the cup and bounded by the annular orifice and said guide

providing a chamber for the first piston area; and means including a passage connecting said space and chamber and providing for lagging of pressure changes in the chamber relative to said space.

13. In governing apparatus, a pressure-responsive device; a centrifugal governor including flyweights, spring means, and a thrust member acted on by opposing effects of the flyweights and of the spring means; and a pressure transformer providing transformed fluid pressure for acting on the pressure-responsive device; said transformer including means providing an enclosed transformed fluid-pressure space in communication with the pressure-responsive means and provided with an escape port bounded by a flat surface extending normally with respect thereto, means including an orifice for supplying fluid under pressure to said space, means providing a guide aligned longitudinally with said port and the thrust member, and a member in thrust-transmitting relation with respect to said thrust member and provided with a cup having a thin annular edge cooperating with said flat surface to provide a radially-directed circular escape orifice, said member having a slide portion fitting the guide.

14. In governing apparatus, flyweights, spring means, a thrust member acted on by the resultant of forces due to the flyweights and the spring means, means providing a space for liquid under regulated pressure, said last-named means comprising a housing provided with a bore and a tubular member slidible in the bore toward and away from said thrust member and providing a discharge port for said space, a member in thrust transmitting relation with respect to said thrust

member and provided with a portion arranged in covering relation with respect to said discharge port and cooperating with the discharge end of the tubular member to define an annular escape orifice for said space, means for supplying liquid to said space so that the pressure therein depends upon the flow area of the escape orifice, and means for adjusting the tubular member toward and away from said thrust member to provide, for a given escape area of the annular orifice and the corresponding regulated pressure, a change in speed dependent upon the extent and direction of adjustment.

15. In governing apparatus, flyweights, spring means, a thrust member acted on by the resultant of forces due to the flyweights and the spring means, means providing a space for liquid under regulated pressure, said last-named means comprising a housing provided with a bore and a tubular member slidible in the bore toward and away from said thrust member and providing a discharge port for said space, a member in thrust-transmitting relation with respect to said thrust member and provided with a portion arranged in covering relation with respect to said discharge port and cooperating with the discharge end of the tubular member to define an annular escape orifice, means including a metering orifice for supplying liquid to said space, and means for adjusting the tubular member toward and away from said thrust member to provide, for a given escape area of the annular orifice and the corresponding regulated pressure, a change in speed dependent upon the extent and direction of adjustment.

MANIOUS GOTTLIEB.
